CURTAIN DRYING FRAME

Filed Sept. 30, 1930

INVENTOR

Loren W. Rickey
John A. Plaistow
ATTORNEY

UNITED STATES PATENT OFFICE

LOREN W. RICKEY, OF SANTA CRUZ, CALIFORNIA, ASSIGNOR OF ONE-HALF TO WILLIAM O. KERRICK, OF SANTA CRUZ, CALIFORNIA

CURTAIN DRYING FRAME

Application filed September 30, 1930. Serial No. 485,345.

This invention relates particularly to a drying frame of the type disclosed in my Patent No. 1,555,758, and dated September 29, 1925.

It is the object of the present invention to provide a support for the reversible frame that will permit the frame to be quickly and easily reversed, and that will form a strong and substantial support for the frame in all 10 positions.

It is also an object of the invention to provide supporting means of the character indicated that will be economical to manufacture, simple in form and construction, strong, 15 durable and highly efficient in its practical application.

In the drawing:

Figure 1 is a front elevation of a drying frame embodying my invention, part broken 20 away.

Figure 2 is an end elevation of the same, part broken away.

Figure 3 is an enlarged section on line 3—3 of Figure 2, parts broken away.

25 In the embodiment of the invention herein disclosed, I show at 1 a supporting frame for the heating unit shown in part at 2 and the reversible frame 3 hereinafter more particularly described. Mounted upon the inner sides of the sides of the frame 1, and adjacent their forward edges, are channel irons 3a provided with openings as 5 and 6 at their upper and lower ends as shown.

The frame 3 has curtain stretcher means 35 as 7 and 8 mounted upon its opposite sides and separated by a partition as 9. The stretching means may be of any suitable character and is not described in detail since no claims are drawn thereon. The frame 3 also has rollers as 10 mounted thereon as 40 shown and adapted to pass through openings 5—6 and travel in the channel irons 3a.

The reversible frame is supported upon the main frame 1 in the following manner. 45 Upper and lower arms 11 and 12, respectively, are mounted on frame 1 at the corners thereof and projecting a distance forwardly thereof, the upper arms being substantially half the length of the lower ones. Pivotally 50 mounted on trunnions 13 on opposite sides of

frame 3 are bars 14. Pivotally mounted upon opposite ends of the bars 14 and upon arms 11 and 12 as shown are links as 15 and 16, the links being all of equal length.

The frame 3 is always reversed in the same 55 direction as indicated by arrow 17. This movement causes the lower rollers 10 to travel upwardly in channels 3a and the bars 14 to assume position 18. But when the frame passes the horizontal the bars 14 move 60 back over the same paths over which they advanced until the frame is again disposed in a vertical plane.

By this means it will be observed that the 35 rollers 10 alternately enter the lower openings 6 and pass out of the upper openings 5 as the frame is reversed, and that links 16 take the weight of the frame and move through a relatively small arc intersecting a 70 vertical plane coincident with the axis of links 16. The arms 15 carry a part of the weight of the frame when same is in a vertical position and when in a horizontal position, and steady its movements at all times.

The relative proportions of the several 75 arms and links may, of course, be infinitely varied without departing from the spirit of the invention.

It is to be understood, of course, that while I have herein shown and described but one 80 specific embodiment of the invention, changes in form, construction, and method of assembly and operation may be made within the scope of the appended claims.

I claim:

1. A stretcher frame mounting comprising, a rigid support mounted adjacent each corner of the frame when the frame is in a vertical position, trunnions mounted on opposite sides of the frame, a cross bar mounted on each trunnion, each cross bar having its ends connected by links to two of said supports.

2. A stretcher frame mounting comprising, a vertically disposed supporting frame, a 95 supporting arm projecting forwardly from each corner thereof, a link pivotally mounted on each arm, a bar pivotally connecting the adjacent ends of the links on each side of the frame, and a drying frame journaled in 100

the bars and having slidable engagement with the supporting frame at one end.

3. A stretcher frame comprising, a supporting frame, a supporting arm projecting forwardly from each corner of the face thereof, one pair of arms being longer than the other pair, a link pivotally mounted on each arm, a cross bar pivotally connecting the adjacent ends of the links on each side of the frame, and a drying frame journaled in the cross bars and having slidable engagement with the supporting frame at one end.

LOREN W. RICKEY.
